Primary Examiner — Steven J Czyz(74) *Attorney, Agent, or Firm* — Foley Hoag LLP;
Stephen J. Kenny(57) **CLAIM**

The ornamental design for walker apparatus, as shown and described.

DESCRIPTION

FIG. 1 is a front perspective view of the walker apparatus showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines depicted in the drawings depict environmental structure and do not form any part of the claim.
